US0D1012616S

(12) **United States Design Patent** (10) **Patent No.:** **US D1,012,616 S**
(45) **Date of Patent:** **** Jan. 30, 2024**

(54) **WATER BOTTLE**

(71) Applicant: **SHENZHEN SITELAI TECHNOLOGY CO., LTD.**, Shenzhen (CN)

(72) Inventor: **Qiuting Luo**, Shenzhen (CN)

(73) Assignee: **SHENZHEN SITELAI TECHNOLOGY CO., LTD.**, Shenzhen (CN)

(**) Term: **15 Years**

(21) Appl. No.: **29/820,428**

(22) Filed: **Dec. 22, 2021**

(30) **Foreign Application Priority Data**

Dec. 16, 2021 (CN) 202130834190.8

(51) **LOC (14) Cl.** **07-01**

(52) **U.S. Cl.**

CLAIM

The ornamental design for a water bottle, as shown and described.

DESCRIPTION

FIG. 1 is a perspective view of a water bottle showing my new design;

FIG. 2 is another perspective view thereof;

FIG. 3 is another perspective view thereof;

FIG. 4 is a front elevational view thereof;

FIG. 5 is a rear elevational view thereof;

FIG. 6 is a left side elevational view thereof;

FIG. 7 is a right side elevational view thereof;

FIG. 8 is a top plan view thereof; and,

FIG. 9 is a bottom plan view thereof.

1 Claim, 9 Drawing Sheets
